ROTARY SLIDE RULE INTERVAL INDICATOR
Marcel Aubert, 1793 SW. 5th St., Miami, Fla.
Filed Jan. 28, 1960, Ser. No. 5,250
8 Claims. (Cl. 235—88)

This invention relates to a rotary slide rule interval indicator for determining intervals of fecundity and sterility in the human female after the theory of Ogino-Knaus.

The principal object of the invention is to provide a slide rule of the above nature which will be simple in construction and easy to use in determining, in advance, calendar intervals of fecundity and sterility in women.

Another object is to provide a device of the character described that is readily adjustable for use by women whose normal menstrual cycles vary widely from the average 28 day cycle.

Yet another object is to provide an indicator which permits accurate determination, in advance, of the beginning date of the next menstrual cycle.

Other objects, features and advantages of the invention will be apparent from the following description when read with reference to the accompanying drawings. In the drawings, wherein like reference numerals denote corresponding parts throughout the several views:

FIG. 1 is a plan view of a rotary slide rule indicator device embodying the invention.

FIG. 2 is a vertical cross-sectional view taken along the line 2—2 of FIG. 1 in the direction of the arrows.

FIG. 3 is a plan view showing the two lowermost rotatable flat members in superposed position, as if separated along the line 3—3 of FIG. 2, and illustrates constructional details thereof, and

FIG. 4 illustrates the index member separately, in plan view.

Referring now in detail to the drawings, 10 in FIG. 1 designates, generally, an improved rotary slide rule interval indicator embodying the invention, the same comprising four flat, superimposed members 11, 12, 13 and 14 held in assembled relation by and mutually rotatable about a central eyelet 15. The flat members 11, 12, 13 and 14 may be of any thin, strong material, such as a good quality cardboard, or even metal, but preferably are made of sheet synthetic plastic for durability, lightness, and attractiveness.

The lowermost or base member 11 preferably is of rectangular shape and of greater size than the upper members 12, 13 and 14, for convenience in holding while the members 12, 13 and 14 are rotatably adjusted with respect thereto and to each other in use, as hereinbelow described. As illustrated in FIG. 3, the base member 11 is printed or otherwise marked on its upper face with a first arcuate series of numbers 16 extending clockwise from "1" to "31," concentric with the central pivotal opening 17 of said flat members and located in segmental boxes 18 of equal size. The base member 11 is also marked with a second arcuate series of clockwise-extending numbers "3" to "31," indicated at 19, concentric also with the central pivotal opening 17, but at a lesser radius. The second arcuate series of numbers are so rotatively displaced with respect to the first series 16 that the numbers "3" to "15" of said second series are in radial alignment with the numbers "19" through "31" of said first series, and the individual numbers of said second arcuate series are located in segmental boxes 20 of equal size.

The second flat member 12 is generally circular in form and provided with an ear or tab 21 facilitating rotary adjustment with respect to the base member 11 for the purpose hereinbelow explained. The second flat member 12 is provided with a first arcuate opening 22 of such extent and at such a radius from the rotary axis as to expose

2

the first arcuate series of numbers 16 of the base member 11, and a second arcuate opening 23 of such extent and at such a radius from the rotary axis as to expose the second arcuate series of numbers 19 when said first series are exposed (see FIG. 3). The second arcuate opening 23 is wide enough to open into the leading edge of the first arcuate opening 22 to provide an opening of increased width exposing both arcuate series of numbers 16 and 19 where said openings overlap. Printed or otherwise impressed on the second flat member 12 is an arcuate series of numbers 24 extending from the leading edge of the second arcuate opening 23 therein and coaxial with and in radial register with the second series of numbers 19 of the base member 11. The arcuate series of numbers 24 read clockwise from "1" to "30" and then, in consecutive number pairs "1," "31"; "2," "1"; "3," "2"; "4," "3"; "5," "4"; "6," "5"; "7," "6"; "8," "7"; "9," "8"; "10," "9" and "11," "10"; said series of numbers and number pairs being located in segmental boxes 25 equal in size to the segmental boxes 20 of the second arcuate series of numbers 19 on the base member 11.

The third flat member or index member 13 is sectorial in shape and formed with a short arcuate opening 26 so radially spaced from the center of rotation as to expose eight consecutive numbers along the second arcuate series of numbers 19 on the base member 11, as seen through the second arcuate opening 23 of the second flat member 12 or along the arcuate series of numbers 24 on the second flat member 12 or, along both said arcuate series where they join, depending upon the particular setting of the device. The index member 13 is provided with an index line 27 extending radially from the center of the outer peripheral edge of the arcuate opening 26, and an adjustment tab portion 28 extending outwardly beyond the peripheral edge of the second flat member 12, to facilitate rotational adjustment.

The fourth or top flat member 14 is circular in form and provided with an arcuate opening 29 concentric with the axis of rotation and about 180 circular degrees in extent, said arcuate opening being of such radial disposition as to permit exposure of the second arcuate series of members 19 on the base member 11 and the arcuate series of numbers 24 on the second flat member 12. Printed or otherwise marked on the face of the top flat member 14 along the outer peripheral edge of the arcuate opening 29 thereon, is a series of index arrows 30 marked from "21" to "37," consecutively, in the clockwise direction, and arcuately spaced to the same degree as the individual characters of the arcuate series of numbers on the first and second flat members 11, 12. Also printed or otherwise marked on the face of the top flat member 14 along the leading portion of the inner peripheral edge of the arcuate opening 29 is an arcuate series of numbers from "21" to "37," designated by reference character 31, also arcuately spaced to the same degree as the individual character of the arcuate series of numbers on the first and second flat members 11, 12. Cut in the top flat member 14 approximately diametrically opposite the arcuate opening 29 therein is a substantially rectangular opening 32 of such size and radial position as to expose one at a time only of the number boxes 18 of the first arcuate series of numbers 16 in the base member 11.

In use, the second flat member 12 will first be turned with respect to the base member 11, by means of the tab or ear 21, so that the number "1" of the arcuate series of numbers 24 on the second flat member 12, corresponding to the days of the new month, is next to the last day of the last menstruation month as indicated by the members "28," "29," "30" or "31" of the second series of arcuate numbers 19 on the first member 11. In the embodiment illustrated in FIG. 1 it will be seen that number "1" of the arcuate series 24 is set next to the number "30"

(corresponding to a thirty day previous month) of the series 19, by way of example. The fourth or top member 14 will then be turned so that the opening 32 therein is over the date of the beginning of the last menstruation (the 18th day of the month as illustrated by way of example in FIG. 1). The index member 13 will then be moved so that its index line 27 is in line with the index arrow 30 corresponding to the cycle of the user (the number of days between menstruations). In FIG. 1, it will be seen that the index line 27 of the index member 13 is set, by way of example, for a 28 day cycle. The dates of fecundity can then be read within the arcuate opening 26 of the index member 13. The days of fecundity thus are the 27th, 28th, 29th and 30th of the month during which menstruation takes place, and the 1st, 2nd, 3rd and 4th of the following or new month. If the cycle of the user varies, the days of fecundity can be computed as from the first day of the shortest cycle to the last day of the longest cycle.

Means is also provided for indicating the beginning day of the next menstruation. To this end, the sector shaped index member 13 is provided with a leading edge portion 33 which, when the computer is set as hereinabove described, marks the date of the beginning of the next menstruation on the arcuate series of numbers 24 on the second flat member 12 as seen through the arcuate opening 29 in the top flat member 14. Thus, as illustrated in the example of FIG. 1, this will be the 16th of the following or new month for the 28 day cycle.

While I have illustrated and described herein only one form in which the invention can conveniently be embodied in practice, this embodiment is presented by way of example only and not in a limiting sense. In short, the invention is limited only by the spirit and scope of the following claims.

What I claim as new and desire to secure by Letters Patent is:

1. A rotary slide rule indicator comprising, in combination, four flat members arranged in face-to-face superimposed relation, means constraining said flat members to rotary motion about a common rotational axis normal to the faces of said flat members, the first of said flat members being the bottom member and having impressed thereon a first arcuately arranged consecutive series of numbers coaxial with said common rotational axis, said first flat member having impressed thereon a second arcuately arranged consecutive series of numbers coaxial with said common rotational axis and radially and arcuately displaced with respect to said first arcuately arranged series of numbers, the second of said flat members having first and second arcuate openings coaxial with said common rotational axis, the arcuate extent and radial disposition of said arcuate openings being such that, for a given rotary position of said second flat member with respect to said first flat member, said first arcuate opening will expose said first arcuate series of numbers and said second arcuate opening will expose said second series of numbers, said second flat member having impressed thereon a first arcuately arranged consecutive series of numbers coaxial with said common rotational axis and beginning from one end of said second arcuate opening and at a radius equal to that of said second series of numbers, said third flat member having a relatively short arcuate opening coaxial with said common rotational axis and at the radius of said second series of numbers of said

first member and the first series of numbers of said second member, said fourth or top member having an arcuate opening coaxial with said rotational axis and of substantially 180 circular degrees in extent at such a radius as to expose said short arcuate opening in said third flat member, an opening in said fourth member substantially diametrically opposite said arcuate opening therein and at such a radius with respect to said rotational axis and of such a size as to expose one at a time of the individual members of said first arcuate series of numbers of said first member, and numerical indicia on said fourth member for rotatively setting said third member with respect thereto at a number corresponding to a cyclic period.

2. A rotary slide rule indicator as defined in claim 1 wherein said numerical indicia comprises a first consecutive series of arcuately arranged numbers adjacent said arcuate opening in said fourth member and an index line extending radially centrally of said short arcuate opening of said third member, said short arcuate opening being of such length as to expose a whole number of a plurality of consecutive numbers of said second series of numbers on said first flat member or said series of numbers on said second flat member, selectively.

3. A rotary slide rule indicator as defined in claim 2 wherein said third flat member is in the shape of a sector and has a leading edge portion which extends to and marks off an individual number of said second series of numbers on said first flat member or an individual number of said series of numbers on said second flat member, selectively, said marked off number being in advance of the numbers exposed by said short arcuate opening by a predetermined amount of whole numbers.

4. A rotary slide rule indicator as defined in claim 3 including a second arcuately arranged series of numbers along an arcuate edge portion of said arcuate opening of said fourth member, corresponding to said first consecutive series of arcuately arranged numbers thereon and in advance thereof to such a degree and so spaced as to be correspondingly indexed by the leading edge of said third member to the cyclic period number of said first arcuate series of numbers on said fourth member to which said third member is set.

5. A rotary slide rule indicator as defined in claim 2 wherein said arcuately arranged consecutive series of numbers all increase in the clockwise direction along their respective flat members.

6. A rotary slide rule indicator as defined in claim 5 wherein said second flat member is generally circular in shape and provided with an integral peripheral tab facilitating rotation thereof with respect to said first flat member.

7. A rotary slide rule indicator as defined in claim 6 wherein said fourth member is circular in shape and wherein said third flat member is provided with an integral tab extending outwardly of the periphery of said fourth flat member for facilitating rotational adjustment thereof with respect to said fourth flat member.

8. A rotary slide rule indicator as defined in claim 7 wherein said first flat member is rectangular in shape and of greater size than of said second, third and fourth flat members.
